Primary Examiner—Susan J. Lucas*Assistant Examiner*—Cynthia E. Ramirez*Attorney, Agent, or Firm*—Westman, Champlin & Kelly, P.A.; S. Koehler[57] **CLAIM**

The ornamental design for a support frame for a mechanical wedge grip, as shown and described.

DESCRIPTION

FIG. 1 is a perspective view for a support frame for a mechanical wedge grip showing our new design;
 FIG. 2 is a top plan view thereof;
 FIG. 3 is a bottom plan view thereof;
 FIG. 4 is a side elevational view, the other side being a mirror image;
 FIG. 5 is a front elevational view; and,
 FIG. 6 is a rear elevational view thereof.
